REGINALD B. MILDON, OF LANSDOWNE, PENNSYLVANIA, ASSIGNOR TO WESTINGHOUSE ELECTRIC AND MANUFACTURING COMPANY, A CORPORATION OF PENNSYLVANIA

UNDERFEED STOKER

Application filed February 21, 1930. Serial No. 430,362.

My invention relates to progressive feed stokers, and more particularly to the multiple retort underfeed type. At the present time, all stokers of this type, of which I have knowledge, are so constructed that the tuyère rows are supported by the retort side walls. The object of my invention is to support the tuyère rows by means independent of the retort side walls, the supporting means being 10 below the tuyère rows and not in contact with the fuel. My invention contributes the following advantages to a stoker:

1. Permits relative movement of the parts due to unequal expansion.
- 15 2. Facilitates repair and replacement.
3. Localizes trouble in the retort in case the retort walls are burned.

This and other objects are effected by my invention, as will be apparent from the following description and claims taken in connection with the accompanying drawings, forming a part of this application, in which:

Fig. 1 is a longitudinal sectional view of stoker apparatus constructed in accordance 25 with my invention, the view being taken on the section line I—I of Fig. 2;

Fig. 2 is a fragmentary plan view of the apparatus shown in Fig. 1, certain parts being removed to illustrate detail construction;

30 Fig. 3 is an enlarged fragmentary sectional view taken on the line III—III of Fig. 1; and,

Fig. 4 is a fragmentary sectional view taken on the line IV—IV of Fig. 1 and illustrating the details of the structure at the lower end of the stoker.

According to a preferred embodiment of my invention which is shown on the accompanying drawings, I provide a multiple-retort underfeed stoker having alternately-arranged retorts and tuyère rows wherein the tuyères are supported by means located between walls of adjacent retorts and independently of the latter.

45 Referring now in detail to the construction illustrated, I show, by way of example, a pair of spaced, parallel I-beams 10 and 11 disposed transversely beneath the front and rear, respectively, of a multiple-retort underfeed

50 stoker 12. The beams 10 and 11 form the

main supporting structure for the stoker. The stoker comprises alternately-disposed parallel retorts 13 and rows of tuyères 14 and consist in general of two parts: (1) a steel frame out of contact with the fuel bed, and 55 (2) a cast iron fuel-supporting grate formed in sections and detachably secured to the steel frame.

The steel frame comprises pairs of spaced, parallel angle beam members 15 and I-beam 60 members 16 parallel to the beams 15 and so arranged that one of the I-beam members 16 is disposed between adjacent pairs of angle beam members 15. The beam members 15 and 16 are secured at their front and rear to 65 castings 17 and 18, respectively, which latter are supported by the I-beams 10 and 11.

The length of the castings 17 and 18 determine the width of the retorts. The castings 17 are disposed in abutting side-by-side 70 relation and are bolted to the I-beam 10. The castings 18 are also disposed in side-by-side relation, but are free to slide upon the lower I-beam 11, so as to permit longitudinal expansion of the stoker. 75

The fuel-supporting surface or combustion grate is formed by the walls of the retort and the tuyères. These parts are made of cast iron and are sectional so as to resist the heat of the furnace and to permit the ready assembly and replacement thereof.

80 A plurality of upright cast iron plates 20 are bolted to the vertical sides of each angle member 15 and form sectional side walls for the retorts. The ends of adjacent plates 20 85 forming each side wall are secured together by clamping plates 21 and bolts 22, the lower ones of the bolts 22 serving also to secure the plates 20 to the angles 15. The bottom wall of each of the retorts is formed by plates 23 disposed between the side walls thereof. The bottom walls may be supported directly by the retort side walls. Preferably, however, such bottom walls are supported by cast iron blocks 24 which are bolted to the lateral 90 flanges of the pairs of angle members. 95

Supported by the upper face of the I-beams 16 are one or more elongate rectangular castings 25 comprising a bottom plate 26 bolted to the beam 16, parallel side pieces 27 and 100

cross pieces 28 connecting the side pieces to the bottom plate. Tuyères 29 are disposed in overlapping relation to one another and are supported directly by the side pieces 27 of the rectangular castings 25. The tuyères 29 are provided with lugs 30 which engage lugs 31 formed on the inner sides of the side pieces 27. The tuyères are also provided with depending lugs 32, which fit within slots 33 provided on adjacent tuyères. The coacting lugs 30 and 31, and the lugs 32 and slots 33 serve to hold the tuyères in proper assembled relation.

By reason of the fact that the retort side walls are constructed in several sections and are bolted to a supporting frame structure, and the tuyères are carried by separate and independent supporting frame structures, all of the parts exposed to the fire are permitted to expand and contract relative to one another. Also by reason of this construction, the retort side and bottom walls may be removed without disturbing the rows of tuyères. This latter is especially advantageous from the viewpoint of maintenance for the reason that in the prior art construction, it was necessary to remove the tuyères before removing the retort side wall.

While I have shown my invention in but one form, it will be obvious to those skilled in the art that it is not so limited, but is susceptible of various changes and modifications without departing from the spirit thereof, and I, therefore, desire that only such limitations shall be placed thereupon as are imposed by the prior art or as are specifically set forth in the appended claims.

What I claim is:

1. In a stoker formed of parallel and alternately-disposed rows of tuyères and retorts, the combination of a supporting means; plates secured to the supporting means to form retort side walls; a second supporting means; and tuyères bridging the distance between the side walls of adjacent retorts and supported solely by said second supporting means.

2. In a stoker formed of parallel and alternately-disposed rows of tuyères and retorts, the combination of a supporting structure arranged out of contact with the fuel; plates secured to the supporting structure and forming sectional side walls of the retorts; a second supporting structure also arranged out of direct contact with the fuel; tuyères bridging the distance between the side walls of adjacent retorts and supported solely by said second supporting structure.

3. In a furnace, the combination of a supporting structure disposed transversely of the furnace and adjacent one wall thereof; a second supporting structure disposed in spaced, parallel relation to the first supporting structure and at a lower level; and a downwardly-inclined multiple-retort under-

feed stoker carried by the two supporting structures and comprising a plurality of pairs of spaced, substantially parallel beam members carried by the two supporting structures, other beam members parallel to the pairs of beam members and also carried by the supporting structures and arranged so that at least one of said other beam members is disposed between adjacent pairs of the first-named beam members, a plurality of upright plates detachably secured to each of the first-named beam members to form sectional retort side walls, means disposed between alternate adjacent retort side walls and providing bottoms for the retorts, and tuyère structures bridging the entire space between the side walls of adjacent retorts and supported solely by said other beam members whereby the side walls of the retorts may be inserted and removed without disturbing the tuyère structures.

4. In a stoker, the combination of a first supporting structure, upright plates carried by said supporting structure to form parallel spaced retort side walls, bottom forming members disposed between alternate adjacent pairs of retort side walls, a second supporting structure, and a series of tuyère plates bridging the space between each of the remaining pairs of retort side walls and carried entirely by said second supporting structure, whereby the retort side wall may be removed without disturbing the tuyères.

5. In a stoker, the combination of a stationary first supporting structure, upright plates detachably secured to said structure to form stationary, parallel, and spaced retort side walls, bottom forming members disposed between alternate adjacent pairs of retort side walls, a second stationary supporting structure, and a series of tuyère plates bridging the space between each of the remaining pairs of retort side walls and detachably secured and supported entirely by said second supporting structure, whereby the retort side walls may be removed without disturbing the tuyères.

In testimony whereof, I have hereunto subscribed my name this 17th day of Feb., 1930.

REGINALD B. MILDON.
